UNITED STATES PATENT OFFICE

LEONIDAS P. HOBBS, OF HOUSTON, TEXAS

NEWSPAPER RACK

Application filed January 28, 1927. Serial No. 164,175.

This invention relates to new and useful improvements in a newspaper rack.

One object of the invention is to provide a rack, or holder, for a newspaper by means of which the paper may be held in position so that it may be easily read while the reader is engaged in some other occupation. The holder is specially provided for use in restaurants and other like places for the purpose of holding the newspaper in front of the reader so that it may be readily perused while the reader is eating, but it is also capable of general use.

Another object of the invention is to provide a newspaper holder or rack, which may be readily folded up in collapsed position when not in use so that it will occupy a small space.

With the above and other objects in view the invention has particular relation to certain novel features of construction, arrangement of parts, and use, an example of which is given in this specification and illustrated in the accompanying drawings, wherein:—

Figure 1 shows a front elevation of the device, and

Figure 2 shows a side view thereof.

Referring now more particularly to the drawings, wherein like numerals of reference designate similar parts in each of the figures the numerals 1, 1, designate the front legs thereof, whose lower ends have the supporting feet 2, 2. Pivoted to the upper end of one of the legs 1 there is a cross bar 3 and the upper end of the other leg 1 has a clamplike bracket 4 secured to the rear side thereof in which the free end of the bar 3 is adapted to rest but from which it may be readily disengaged, as is illustrated in Figure 2. Fastened to the rear side of the upper end of each leg 1, beneath the bar 3, are the hood like bearings 5 which diverge downwardly from the legs 1 and in which the upper ends of the rear supporting legs 6 are pivoted. The lower edge of each hood 5 forms a stop for the corresponding leg 6, which limits the outward movement of said legs, the legs 6 when in use diverging downwardly from the legs 1 and forming rear supports for the rack. There are the cross links 7 and 8 which are pivoted

at their lower ends to the respective legs 1, and whose upper ends have the pintles 9, 9, which run in the elongated vertical slots 10, 10, in the legs 1 and these links 7 and 8 are pivotally connected together at their centers by the pivot pin 11. Fastened to the front sides of the legs 1, at their lower ends, are the spring clamps 12, 12. The upper ends of these clamps are outwardly turned, as at 13, to permit the easy insertion of the paper 14 between said clamp and the legs 1, as illustrated in dotted lines in Figure 2. There is a support 15 preferably formed of a looped wire which is fastened at its lower end to the pivot pin 11 and which is adapted to lie against the rear side of, and support the paper 14.

When not in use the cross bar 3 may be disengaged from the bracket 4 and swung down into alignment with the leg 1, to which it is pivoted, and the legs may be then moved together, the pintles 9, during this movement, moving to the upper ends of the slots 10 so that the rack may be collapsed and the rear legs 6 may be then swung closely against the legs 1 so that the rack, when fully collapsed, will occupy a very small space.

What I claim is:—

1. A newspaper rack, including front supporting legs, rear supporting legs pivoted at their upper ends to the respective front legs intermediate their ends, cross links pivoted together and pivotally connected at one end to the front legs and whose other ends have a slidable connection with said front legs, a cross bar pivoted to one leg and slidably connected with the other leg, spring clamps rigidly secured to said front legs near their lower ends and adapted to clamp a paper between them and said front legs and also to support said paper and a support carried by said cross links.

2. A newspaper rack, including front supporting legs having oblong slots therein, rear supporting legs pivoted at their upper ends to the respective front legs, cross links pivoted together near their centers and pivotally connected at one end to the front legs and whose other ends have pintles having a slidable connection with said slots in the front legs, a

cross bar connecting said front legs, spring clamps rigidly secured at their lower ends to said front legs and adapted to clamp a paper between them, and said front legs, to prevent the paper from slipping down, a rear support for the paper pivotally connected to said cross links.

3. A newspaper rack including front supporting legs having oblong slots therein, rear supporting legs pivoted at their upper ends to the rear sides of the front legs, a cross bar pivoted at one end to one of the front legs, a bracket carried by the other front leg adapted to engage the other end of said bar, cross links pivoted together, said links being pivoted at one end to the front legs and their other ends having pintles having a slideable connection with the front legs through said slots, means carried by the front legs for clamping a newspaper on said rack and also for preventing said paper from slipping down.

4. A newspaper rack including front supporting legs which are provided with oblong slots, rear supporting legs pivoted at their upper ends to the rear sides of the front legs intermediate their ends, a cross bar pivoted at one end to one of the front legs, a bracket carried by the other front leg adapted to engage the other end of said bar, cross links pivoted together, said links being pivoted at one end to the front legs and their other ends having pintles having a slideable connection with slots in the front legs, means carried by the front legs for clamping a newspaper on said rack and a rear support for the newspaper, carried by said links.

In testimony whereof I have signed my name to this specification.
